ATTORNEY

tween these guides as the tips 12 are moved into proximate relationship (see FIG. 1). Also, the lateral guides act as a gauge to the width of the implanted object (as a bone graft).

Although I have described my instrument in detail with respect to orthopedic surgery, it may be used in other applications where it is desired to distract (separate) closely adjacent objects and move an insertable object into a final position between the distracted objects.

I claim:

1. In an orthopedic surgical instrument:

- (a) a supporting frame having a pair of arms mounted for movement toward and away from one another, the arms extending generally lengthwise with respect to each other, each arm being provided with a tip at its forward end, the tips being movable into proximate relationship relative to one another so that they may be inserted between closely adjacent vertebral bodies;
- (b) the arms defining a channel therebetween into which a bone graft may be inserted;
- (c) operating means actuatable to spread the tips apart so as to distract said adjacent vertebral bodies to provide sufficient space therebetween for reception of the bone graft, and at the same time advancing the bone graft into a final position between the distracted vertebral bodies, the arms and tips being located to engage with and guide the bone graft forwardly to its final position;
- (d) a pair of spaced lateral guides provided on opposite sides of the supporting frame and located to hold the bone graft between the arms as the bone graft is advanced, the lateral guides and arms acting as a protective retractor to adjacent soft tissues of an incision made in the patient to reach said vertebral bodies;
- (e) the lateral guides defining forward ends that are located to engage with one of said vertebral bodies to limit insertion of the tips between the vertebral bodies;
- (f) and the lateral guides being secured to one of the arms and disposed so that the other arm will pass between these guides as the tips are moved into proximate relationship.

2. The orthopedic surgical instrument, as set forth in claim 1;

(g) and in which the supporting frame is made from resilient material, with the arms and their tips being biased toward one another so as to yieldingly maintain contact with the bone graft as the latter is advanced between and projects beyond the tips.

3. The orthopedic surgical instrument, as set forth in claim 1;

(g) and in which adjustable means are provided to limit the depth of insertion of the bone graft between said distracted vertebral bodies.

4. The orthopedic surgical instrument, as set forth in claim 1;

(g) and in which a handle is provided on the supporting frame that may be grasped by a surgeon to hold the instrument in place;

(h) the operating means comprising:

- (1) a rod threaded through the handle and having a forwarded section projecting into the space between the arms, the rod being advanced toward the tips when the rod is turned in one direction and retracted relative to the tips when the rod is turned in the opposite direction;
- (2) and a sliding block disposed between the arms and being anchored to the forward end of the rod in a position to engage with and advance the bone graft between and forwardly of the tips with sufficient force to insert the bone graft into its final position between the distracted vertebral bodies.
